UNITED STATES PATENT OFFICE.

CHARLES OTIS GRIFFIN, OF NEWBERN, NORTH CAROLINA.

TOY BALL.

1,236,290.

Specification of Letters Patent.

Patented Aug. 7, 1917.

Application filed January 4, 1917. Serial No. 140,562.

To all whom it may concern:

Be it known that I, CHARLES OTIS GRIFFIN, a citizen of the United States, and a resident of Newbern, in the county of Craven and State of North Carolina, have invented an Improvement in Toy Balls, of which the following is a specification.

My invention is an improvement in toy balls, and has for its object to provide a ball of the character specified, wherein a ball is provided having thereupon the representation of a face or faces, and wherein a sectional cover of elastic material is provided, which may be placed on the ball to cover the same or may be removed, and wherein a cord is connected with the ball and adapted to be wound thereupon beneath the cover or partially beneath the same, the cover sections being adapted to form a bust and a head covering for the figure, and wherein the ball proper may be hollow and provided with a whistle, and with means therein for causing a rattling when the ball is shaken.

25 In the drawings:

Figure 1 is a front view of the ball with the cover sections used as head covering and bust, showing one of the faces.

Fig. 2 is a similar view showing the other face.

Fig. 3 is a front view of the ball with the covers in place and with the cord beneath the cover.

Fig. 4 is a perspective view with the cord extended.

Fig. 5 is a sectional view.

Fig. 6 is a perspective view of the parts detached.

In the present embodiment of the invention, the ball 1 is of rubber, and is provided with a whistle 2 which may be sounded by pressing the ball to force out the air therein. When the pressure is relaxed, the ball will assume its original shape. Within the ball 45 may be arranged bodies indicated at 3, which, when the ball is shaken, will produce a rattling sound.

A cord 4 is connected with the ball, the said cord being of ribbon formed as shown, 50 in order that it may be wrapped smoothly on the ball in the manner shown in Figs. 3 and 5, to permit the placing of the cover sections to be described.

The peripheral surface of the ball is provided with one or more representations of faces, two in the present instance, each face

occupying approximately half the area of the surface of the ball. Cover sections 5 and 6 are provided for covering the ball, the said sections being of flexible rubber, and 60 of semi-spherical form, and each section is provided with a segmental vulcanized portion 7 at its center. These sections are of a size and are shaped to fit closely over the ball in the manner shown in Figs. 3 and 4, 65 and they are also arranged to be reversed to form a bust and head covering for the representations of the faces.

The section 5 is provided on its inner face with shade lines to indicate portions of 70 clothing, to complete with the face representation the representation of a figure, as shown in Figs. 1 and 2, and the other section 6, of the cover, may be reversed, as shown in said Figs. 1 and 2 to provide a 75 head covering. When the section 5 is used as a bust or base for the ball, the cord is wrapped around the neck, that is, is wound between the ball and the cover section. The improved ball may be used as a figure, or as 80 a ball without the covers, or as a ball with the covers, or as a return ball when the cord is extended. With the bodies 3 the ball is converted into a rattle. The ball may be used as a return ball either with or without 85 the covers.

It will be understood that a series of coverings might be provided, the sections of each series having representations of faces thereon, and that the covers might be arranged one upon the other in the same manner as the layers of an onion, or that the cover sections might be interchangeable.

I claim:

1. A toy ball comprising an elastic hollow 95 ball having a whistle and a rattle, and having the representation of a plurality of faces on its surface, and having a cord connected therewith, and flexible elastic semi-spherical covers for the ball, each cover having a portion at the center thereof vulcanized.

2. A toy ball comprising an elastic hollow ball having the representation of a plurality of faces on its surface, and having a cord 105 connected therewith, and flexible elastic semi-spherical covers for the ball, each cover having a portion at the center thereof vulcanized.

3. A toy ball comprising a ball having a 110 representation of a face on its surface, and having a cord connected therewith, and

flexible elastic semi-spherical covers for the ball, each cover having a portion at the center thereof vulcanized.

4. A toy ball comprising a ball having a representation of a face on its surface, and having a cord connected therewith, and flexible elastic semi-spherical covers for the ball.

5. A toy ball comprising a ball having a

representation of a face on its surface, and flexible elastic semi-spherical covers for the ball.

6. A toy ball comprising a ball, and flexible elastic semi-spherical covers for the ball.

CHARLES OTIS GRIFFIN.
